STARTING UNLOADER FOR MULTISTAGE COMPRESSORS

Harry V. Haight, Ashton-on-Mersey, England,
assignor to Ingersoll-Rand Company, Jersey
City, N. J., a corporation of New Jersey

Application November 11, 1935, Serial No. 49,207

1 Claim. (Cl. 230—29)

This invention relates to compressors, but more particularly to an unloader for compressors of the multi-stage type.

One object of the invention is to relieve the load of the prime mover of the compressor during the starting period of the compressor.

Another object is to effect such unloading of the compressor in a simplified manner and with a minimum number of parts.

10 Other objects will be in part obvious and in part pointed out hereinafter.

In the drawings accompanying this specification and in which similar reference numerals refer to similar parts,

15 Figure 1 is an end elevation of a compressor equipped with an unloader constructed in accordance with the practice of the invention,

Figure 2 is a side elevation of the compressor partly broken away, and

20 Figure 3 is an elevation, in section, of the unloader.

Referring more particularly to the drawings, the compressor, designated by 20, comprises the usual bed plate 21 and low and high pressure cylinders 22 and 23, respectively. The cylinders are arranged on the bed plate in V-fashion and may be secured thereto in any suitable manner.

Each cylinder contains a piston of which only that designated 24 in the high pressure cylinder 23 is shown. The pistons may be connected, in a well known manner, to the crank shaft 25 and to which the prime mover, as for instance an electrical motor 26, may be directly connected for driving the compressor.

35 The low pressure cylinder is provided with an inlet conduit 27 through which fluid medium intended to be compressed enters the compressor from a source and upon compression in the cylinder 22 such fluid is discharged into a manifold 28 connected to the discharge opening of the cylinder 22, whence it passes through an inter-cooler 29 to the inlet opening of the high pressure cylinder 23. Upon being compressed to a higher pressure in the latter cylinder the fluid passes 45 through a discharge conduit 30 into a storage receiver 31.

In accordance with the present invention, means are provided for relieving the motor 26 from the strain of starting the compressor when loaded and to prevent the application of the load to the compressor until the motor approaches or reaches normal speed. To this end the inter-cooler, or more particularly the manifold 28, is 50 provided with an outlet opening in the form of a

tubular member 32 of which the interior or passage 33 serves to convey fluid from the manifold.

The tubular member 32 supports a valve mechanism 34 of which a casing 35 is threadedly connected to an intermediate portion of the tubular member. The lower end 36 of the member 32 projects into a chamber 37 in the casing 35, and in the side of the chamber 37 is an outlet opening, illustrated as being in the form of a conduit 38, which may open directly to the atmosphere or to a source of fluid medium.

The casing 35 consists of an upper section 39 threaded to the tubular member 32 and a lower section 40 secured to the section 39, as by bolts 41. A flexible diaphragm 42 is clamped between 15 the casing sections to seal the chamber 37 from a chamber 43 in the casing section 40.

The diaphragm 42, which may be capable of a considerable degree of movement in the casing 35, carries a valve 44 to control the outlet opening 20 of the passage 33. The valve is secured to the diaphragm by a bolt 45. It is arranged in a plate 46 upon which is seated a spring 47 arranged about the lower end 36 of the tubular member to open the valve. On the lower surface 25 of the diaphragm is a plate 48 which is clamped to the diaphragm by the bolt 45 and seats against a hollow boss 49 in the chamber 43 for limiting the opening movement of the valve 44.

The surface of the diaphragm confronting the 30 chamber 43 constitutes a pressure surface 50 which is subjected to pressure fluid admitted to the pressure chamber 43 directly from the high pressure cylinder 23. Such pressure fluid is conveyed to the chamber 43 by a conduit 51 which 35 communicates constantly with the upper end of the high pressure cylinder 23 through a passage 52 and with the chamber 43 through a port 53. Thus, in operation, pressure fluid may flow directly from the high pressure cylinder 23 through 40 the conduit 51 into the chamber 43 and act against the pressure surface 50 for holding the valve 44 in sealing relationship with the outlet opening of the tubular member 32 to normally prevent the flow of the lower stage discharge 45 pressure to the atmosphere.

In order, however, to assure the retention of a suitable pressure in the chamber 43 to maintain the valve 44 in the sealing position it is essential 50 that the pressure fluid employed for this purpose be restrained from again returning to the high pressure cylinder 23 during the suction stroke of its piston 24. The conduit 51 is accordingly provided with a delay valve mechanism 54 com- 55

prising a casing 55 into the ends of which are threaded sections of the conduit 51.

Within the casing 55 are a pair of passages 56 and 57 of which the passage 56 is in direct communication with a portion of the conduit 51 connected to the chamber 43, and the passage 57 communicates directly with the conduit leading to the high pressure cylinder 23. The passages 56 and 57 communicate with each other through ports 58 and 59. The function of the port 58 is that of a discharge port for the passage 57 and said port is controlled by a check valve 60 arranged in a recess 61 at the outlet end of the port 58. The opening movement of the valve 60 is resisted by a spring 62 extending into and guided by a bushing 63 threaded into the casing 55.

The port 58 serves as a discharge port for the passage 56. Its inlet end is in the form of a tapered portion 64 to conform to the end of a needle valve 65 extending thereinto to define the flow area of the port 58. The needle valve is threaded into the casing 55 and locked in position, in the present instance, by a cap nut 66 which seats against the side of the casing 55 to prevent loss of pressure fluid along the threads of the needle valve to the atmosphere.

Any suitable means may be employed for venting the conduit 51 to the atmosphere or a source 30 of fluid medium in order to provide an escape for pressure fluid from the chamber 43 and from the cylinder 23 at the end of an operating period in order to relieve the compressor of its load for a subsequent period of operation. The means 35 illustrated for this purpose comprises a valve cage 67 to which is connected a branch of the conduit 51 and containing a ball valve 68 for controlling a discharge port 69 in the valve cage.

The valve cage is preferably arranged concentrically with respect to the crank shaft 25 of the compressor and in the end of the drive shaft is a plunger 70 having a reduced projection 71 which extends loosely into the port 69 to unseat the ball valve 68. The plunger 70 is actuated, 45 to perform this function, by a spring 72 and is normally held in retracted position by centrifugal weights 73 mounted on pivots 74 carried by the crank shaft 25.

The operation of the device is as follows: Let 50 it be assumed that the compressor is at rest and that the plunger 70 is then actuated, by the spring 72 to unseat the valve 68. With the ball valve in this position the high pressure cylinder 23 and the chamber 43 will be in direct communication with the atmosphere. The valve 44 will then be held in its open position by the spring 47, and the chambers and passages between the discharge side of the low pressure cylinder and the inlet side of the high pressure cylinder will 55 also be in direct communication with the atmosphere.

If then the compressor be set in operation the inter-cooler will remain completely unloaded, and the fluid medium entering the high pressure cylinder may escape through the conduit 51, the valve cage 67 and through the port 69 to its source. The compressor will continue to operate in this wise until its speed approaches or reaches normal, at which time the centrifugal action of the weight 73 retracts the plunger 70 and the ball valve 68 will then close the port 69 to prevent further passage of fluid to the atmosphere.

Thereafter, the fluid compressed in the high pressure cylinder 23 flows through the conduit 51, passage 57, port 58 and the passage 56 into the chamber 43 and shifts the valve 44 into sealing relationship with the end of the tubular member 32. The manifold and inter-cooler will then be closed and the fluid compressed by the low pressure cylinder passes to the high pressure cylinder where it is compressed to a higher value 20 and discharged into the receiver 31.

During this operation of the compressor the fluid employed for holding the valve 44 seated against the member 32 will be prevented from returning to the high pressure cylinder 23 by 25 the needle valve 65 which will be so adjusted as to allow only a very considerably restricted flow of pressure fluid through the port 58.

When the compressor again ceases operating the spring 72 actuates the plunger 70 and unseats 30 the ball valve 68. The high pressure cylinder will then again be communicated with the atmosphere, and the pressure fluid in the chamber 43 employed for holding the valve 44 closed flows from the chamber 43 through the passage 56, 35 the space defined by the needle valve and the portion 64, thence through the valve cage 67 to the atmosphere to again completely unload the inter-cooler and also the high pressure cylinder 23 preparatory to another period of operation. 40

I claim:

A starting unloader for a compressor having a cylinder operating at a low pressure and a cylinder operating at a higher pressure, an inter-cooler between the cylinders and having an atmospheric vent, a pressure actuated valve to control the vent, a conduit leading from the high pressure cylinder on the cylinder side of the discharge valve thereof to the valve and being in constant communication with the high pressure cylinder, means in the conduit between the high pressure cylinder and the inter-cooler for venting the valve and the high pressure cylinder to the atmosphere for unloading the compressor, and means between the venting means and the valve for restricting the flow of pressure fluid from the valve to the venting means while permitting free flow of fluid from the high pressure cylinder to the valve. 50
